SELF-STANDING CUT-OUT

Arthur H. Torme, Chicago, Ill., assignor to Torme Products Co., Chicago, Ill., a corporation of Illinois

Application October 11, 1935, Serial No. 44,587

6 Claims. (Cl. 46—157)

My invention relates to self standing cutouts. Among the objects of my invention are to provide a cutout that will stand alone without the aid of an easel; to create a cutout having foldable three dimension extremities that will support it in erect position without the aid of a secondary support; to supply a cutout in which an integral part of the cutout itself may be folded to form a supporting portion, said part forming nothing extraneous to the representation on the cutout, and such other objects, advantages and capabilities as will later more fully appear and which are inherently possessed by my invention.

While I have shown in the accompanying drawing a preferred form of my invention, yet I wish it understood that the same is susceptible of modification and change without departing from the spirit of my invention.

Fig. 1 is a perspective view of my cutout blank; Fig. 2 is a perspective view of my cutout in erect position and Fig. 3 is a detailed view of the foldable support portion partially folded.

Referring more particularly to the embodiment selected to illustrate my invention, it comprises a cutout 10 which for purposes of illustration is shown here as a doll or little girl. In my invention I provide adjacent the extremity or extremities of the cutout 10 an integral foldable support portion 11. In the embodiment shown in the drawing a foldable cutout portion 11 continues integrally from the cutout 10 at each of the two feet of the doll, but my foldable cutout portion is not to be limited to use with feet but may be employed with wheels, hands, head, knees, bottom or any other extremity upon which an article or person or thing represented in the cutout might rest.

My foldable support portion 11 has a heel portion 12 continuing forwardly from the cutout 10 and having a horizontal score 13 which permits the heel portion to be bent backwardly until the heel portion is substantially at a right angle to the cutout 10, thus forming a heel for the upright cutout 10. Integral with said heel portion and extending on both sides of said heel portion 12 are a pair of wings 14 and 15. These wings extend on either side of the heel portion along vertical scores 16 and 17 and continue upwardly along the foot 18 of the cutout portion, from which said wings are separated by slits 19 and 20. A diagonal score 21 on one of said wings 14 extends from the lower end of score 16 and meets another diagonal score 22 running from the top 55 of the slit 19, said scores 21 and 22 forming a

triangular portion 23. On the other of the wings 15 a diagonal score 24 extends from the lower end of score 17 and meets another diagonal score 25 running from the top of slit 20 said scores 24 and 25 forming a triangular portion 26.

Extending beyond the triangular portion 23 of wing 14 are a pair of flaps 27 and 28 extending outwardly from scores 21 and 22 respectively. On the other wing 15 are also a pair of flaps 29 and 30 extending beyond the triangular portion 10 26 outwardly from scores 24 and 25.

Substantially in the center of the diagonal scores on one of the wings, and for purposes of illustration shown on the diagonal scores 24 and 25 of wing 15, are a pair of slits 31 and 32. On 15 the wing opposite the wing which has slits 31 and 32 and for purposes of illustration in this case on wing 14 the flaps 27 and 28 have tabs 33 and 34 on their outer portions, said tabs at the point where they join the flaps having scores 35 and 36 respectively.

When it is desired to have my cutout 10 stand the user will bend the heel portion 12 backwardly along the horizontal score 13 so that the heel portion 12 is on the floor or other supporting 25 surface. The wings 14 and 15 are bent inwardly along vertical scores 16 and 17. The flaps 29 and 30 are also bent inwardly along diagonal scores 24 and 25 and said flaps are then pushed inwardly against the foot 18 of the cutout portion 30 10. The flaps 27 and 28 are then bent inwardly along diagonal scores 21 and 22 and said flaps are pushed inwardly against the foot 18 of the cutout 10 so flap 21 of wing 14 folds over flap 29 of wing 15 and likewise flap 28 of wing 14 folds 35 over flap 30 of wing 15. The tabs 33 and 34 then fit into slits 31 and 32 respectively and lock the folding support portion 11 in fixed position. The flaps 28 and 30 form the front portion of the support and flaps 27 and 29 form the back portion 40 of the support, the triangular portions 23 and 26 forming the side portions of the support and the heel 12 together with the bottom edges of the flaps 28 and 30 and the triangular portions 23 and 26 form the bottom portion of my three 45 dimension foldable support 11.

In order to replace the foot of the cutout which is covered by the foldable portion 11 the front flap 28 may bear the simulation of a shoe or the like 35 and the other sides of the foldable support portion 11 may have the simulation of ground, glass, floor or the like.

My cutouts may be constructed of paper, cardboard, metal or any other suitable material and have no appreciable thickness.

- With my structure it will be observed that it is only necessary to have printing on one side and that that side is the same side on which the printed matter of the cutout itself appears.
- 5 It is also a feature of my foldable support portion that it is and need be scored by die cutting on one side only. It is, therefore, so scored that it naturally bends on and with the scores in the desired directions.
- 10 The slits 31 and 32 located respectively on scores 24 and 25 form an opening when said scores are bent sufficiently to admit the tabs 33 and 34 and lock them therein. This form of slit on the score eliminates the need of a small cutout portion which would involve the use of expensive dies in production.
- Having thus described my invention, I claim:
1. A device of the class described comprising a cutout having no appreciable thickness, said 20 cutout having an extremity, a support portion integrally attached to said extremity, said support portion comprising a heel portion adapted to fold backwardly to act as a heel for said cutout, a pair of wings on either side of said heel portion adapted to fold inwardly to form side and front portions of said support portion, said heel, side and front portions forming a three dimension support for and integral with said cutout.
2. A device of the class described comprising a 30 cutout having no appreciable thickness, said cutout having an extremity, a support portion integrally attached to said extremity, said support portion comprising a substantially square section, a horizontal score between said extremity of the cutout and the square section, so that said square section may be bent backwardly to form a heel for said cutout, a pair of wings on either side of said square section, a score on each side of said square section so that said wings may be bent inwardly to close over each other and form side and front portions of said support portion, said heel, side and front portions forming a three dimension support for and integral with said cutout.
- 35 3. A device of the class described comprising a cutout having no appreciable thickness, said cutout having an extremity, a support portion integrally attached to said extremity, said support portion comprising a heel portion adapted to fold backwardly to close over each other and form side and front portions of said support portion, said heel, side and front portions forming a three dimension support for and integral with said cutout.
- 40 45

out having an extremity, a support portion integrally attached to said extremity, said support portion comprising a substantially square section, a horizontal score between said extremity of the cutout and the square section, so that said square section may be bent backwardly to form a heel for said cutout, a pair of wings on either side of said square section, a score on each side of said square section so that said wings may be bent inwardly to close over each other and form side and front portions of said support portion, one of said wings having a pair of slits and the other of said wings having a pair of tabs placed so that when said second wing is folded over said first wing said tabs fit into said slits and lock the wings in fixed position, said heel, side and front portions forming a three dimension support for and integral with said cutout.

4. A doll comprising a body member having extended legs, foldable members secured to the extended legs, said members adapted to fold to form heel, side and front supporting portions to permit said doll to stand vertically, and means for holding said members in releasably folded position.

5. A paper doll comprising a cardboard body having extended legs formed with doll-supporting surfaces, foldable cardboard members secured to the leg extensions, said members adapted to fold to form heel, side and front supporting portions to permit said doll to stand vertically, said members simulating footwear, and means for holding said members in releasable folded position.

6. A paper doll comprising a cardboard body having extended legs formed with doll-supporting surfaces, cardboard members secured to the leg extensions, said members having a plurality of folded lines, one of said members simulating footwear, one of the folded parts forming a heel portion and other of the folding parts forming side and front portions, said heel side and front portions permitting said doll to stand upright, and detachably engageable means for holding said members in folded position.
